CLAIM

The ornamental design for a longhorn skull bootjack, as shown and described.

DESCRIPTION

FIG. 1 is a perspective view of a longhorn skull bootjack, showing my new design;

FIG. 2 is a top plan view thereof;

FIG. 3 is a bottom plan view thereof;

FIG. 4 is an elevational view of one side thereof, the opposite side being a mirror image;

FIG. 5 is a rear end elevational view thereof; and,

FIG. 6 is a front end elevational view thereof.
